US0D1036582S

(12) **United States Design Patent** (10) **Patent No.:** **US D1,036,582 S**
(45) **Date of Patent:** **** Jul. 23, 2024**

(54) **PUSH UP DEVICE**

(71) Applicant: **Zhejiang Aerlang Technology Co., Ltd.**, Jinhua (CN)

(72) Inventor: **Chuanmei Zang**, Jinhua (CN)

(73) Assignee: **Zhejiang Aerlang Technology Co., Ltd.**, Jinhua (CN)

(**) Term: **15 Years**

(21) Appl. No.: **29/861,783**

(22) Filed: **Dec. 2, 2022**

(30) **Foreign Application Priority Data**

Jun. 2, 2022 (CN) 202230335203.1

(51) **LOC (14) Cl.** **21-02**

(52) **U.S. Cl.**

USPC **D21/686**; D21/662; D21/677

(58) **Field of Classification Search**

(57) **CLAIM**

The ornamental design for a push up device, as shown and described.

DESCRIPTION

FIG. 1 is a front, right and top perspective view of a push up device, showing my new design;

FIG. 2 is a perspective view in the folded configuration thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1.

1 Claim, 8 Drawing Sheets
